US00D767243S

(12) **United States Design Patent** (10) **Patent No.:** **US D767,243 S**
Sanctis et al. (45) **Date of Patent:** **** Sep. 27, 2016**

(54) **COATED FOOD PRODUCT**(71) Applicant: **The J.M. Smucker Company**, Orrville, OH (US)(72) Inventors: **Edmond Patrick Sanctis**, Issaquah, WA (US); **Melanie Mitchell Ayles**, Maple Valley, WA (US); **Kathryn Devlin Borgen**, Seattle, WA (US)(73) Assignee: **THE J.M. SMUCKER COMPANY**, Orrville, OH (US)(**) Term: **15 Years**(21) Appl. No.: **29/538,374**(22) Filed: **Sep. 3, 2015**(51) LOC (10) Cl. **01-01**

(52) U.S. Cl.

USPC **D1/101**(58) **Field of Classification Search**

USPC D1/100–130, 199; 426/74, 92–94, 104, 426/134, 138, 143, 275, 277, 279, 281–284, 426/292, 295, 391, 439, 496, 514, 566, 572, 426/660; 249/92; D21/623, 803, 386; 119/710; D7/359; D25/138

CPC . A23L 1/1641; A23L 1/1643; A23L 1/1817; A23L 1/2175
